(57) CLAIM

The ornamental design for handle for a fishing reel, as shown and described.

DESCRIPTION

FIG. 1 is a perspective view of handle for a fishing reel showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 illustrates the design when applied to a fishing reel;

FIG. 9 illustrates the design when applied to another fishing reel.

The broken line showing of environment in FIGS. 8 and 9 is for illustrative purposes only and forms no part of the claimed design.
